C. J. Converse,
Bottle Stopper,
No 85,214. Patented Dec. 22, 1868.

Inventor

Charles J. Converse

CHARLES J. CONVERSE, OF BOSTON, MASSACHUSETTS.

Letters Patent No. 85,214, dated December 22, 1868; antedated December 11, 1868.

IMPROVED BOTTLE-STOPPER.

The Schedule referred to in these Letters Patent and making part of the same.

To all whom it may concern:

Be it known that I, CHARLES J. CONVERSE, of Boston, Suffolk county, State of Massachusetts, have invented a new and improved Stopper for Bottles; and I do hereby declare that the following is a full and exact description of the same, taken in connection with the annexed drawings, with letters of reference marked thereon.

The nature of my invention is that of a stopper for bottles, which stopper, without being removed from the bottle, may, by rotation of the same, admit the influx and efflux of liquids, or other substances, into or out of the bottle.

In the drawings.

Figure 1 is a side view of my bottle, which is made in the usual manner, with a containing-portion below and a neck above, but with some little modifications of both.

B, fig. 1, is a side view of the lower portion of the bottle.

B^X, Figure 5, is a sectional view of the same, taken horizontally.

C, fig. 1, is a side view of the lower part of the neck of the bottle, with sectional view (in dashed lines) of the lower portion of my stopper.

C^X, Figure 3, is a horizontal sectional view of the same.

D, fig. 1, is a side view of the upper part of the neck of the bottle, with sectional view (in dashed lines) of a portion of the upper part of my stopper.

D^X, Figure 4, is a horizontal sectional view of the same.

E, fig. 1, is a side view of the upper part of my stopper.

E^X, Figure 2, is a horizontal sectional view of the same.

Figure 6 is a vertical sectional view of my combined stopper, open.

Figure 7 is a vertical sectional view of the same, when shut.

And the mode of operation of my device is as follows:

I place the bottle A in a sunken recess in a slab of wood, or other substance, which recess is fitted to the cornered shape of the base of my bottle. I then force in the lower portion C of the stopper (the neck-piece) to the position seen in fig. 1, and down upon it I force the upper portion E D, fig. 1. To facilitate this, I make the upper portion of rubber, or other elastic substance, and press it together, when forcing it into its place. The neck-piece may be made elastic or inelastic.

Desiring to fill the bottle, I partially rotate the portion marked E and D, fig. 1 of my stopper, when the through aperture of the same is presented, coincident axially with the perforated aperture of the neck-piece C. There is then a continuous aperture from the body of the bottle to the air, through which I pour into the bottle or discharge from it.

Having finished the filling or the discharging, I par-

tially rotate the upper portion of the stopper, and thus present to the through-aperture of the lower portion C, of my double (or divided) stopper, the solid portion of the upper part, thus effectually stopping either efflux or influx to or from the bottle.

It will be seen that the upper portion E D, of the stopper, is widened at its lower part. This is for the purpose of having sufficient diameter at the base to allow the hole or through-aperture to be of appropriate width, and still be as one side of the axial centre of the stopper. This enlargement below serves another purpose also, for midway between the bottom of the upper stopper and the place to which, when in position, the top of the bottle reaches, is a shoulder on the stopper, fitting against a corresponding shoulder cast on the interior of the neck of the bottle.

And it will be seen, on inspection of the drawings, that the inner sides of the lower part of the bottle-neck, at the point marked C, fig. 1, are octagonal in horizontal section, and the neck-piece is of the same shape. The object of this is to prevent the lower part or neck-piece C being rotated when the upper portion E D is rotated. (I sometimes secure this effect, also, in another way, by making flanges on the sides of the neck-piece C, and corresponding grooves in the inner side of the bottle, and *vice versa*.) And I sometimes use a plate or disk, metallic, or of other substance, instead of the thick neck-piece C.

The upper portion of the stopper, (which is the stopper proper, as distinguished from the neck-piece,) where it enters the bottle, is made (as seen in fig. 4) circular in horizontal section, to facilitate rotation, and the bottle-neck, at that part, (as seen in fig. 4,) is also made circular interiorly.

The portion of the stopper not entering into the bottle, (see E, fig. 2,) is made (in horizontal section) of an octagonal shape, (though I do not confine myself to any number of facets.)

And sometimes I substitute for this arrangement a horizontal flange, with or without a milled periphery.

And I sometimes furnish the top of the stopper with a rigid and unyielding ring or plate, of metal, hard rubber, or other substance, firmly attached to it, to prevent the closing of the through-aperture by twisting of the stopper when rotating it.

The lower part of my bottle, externally, has fourteen facets. (Sometimes I have more, sometimes less.) The object of this is that, in filling the bottle, I may place it in a hole, of corresponding shape, sunk in a board, for convenience in filling the bottle with mineral-water.

For ale, cider, beer, and porter, I do not usually make the bottles cornered at the base.

And I sometimes make my bottle with a glass (or other) diaphragm across the lower part of the neck, with a perforation one side of the centre, blown or firmly fixed into it, thus dispensing with the movable neck-piece C.

I do not claim a vessel, with its lid, cover, or stop-

ple so constructed as that a vent is opened and closed by simply turning the lid, cover, or stopple, or the vessel; nor do I claim the cover of a vessel, composed of two perforated pieces, exposing a vent by partial rotation; and I do not claim an inelastic stopper of any kind.

And what I claim herein as of my own device, and desire to secure by Letters Patent, is—

1. A through-perforated, elastic, rotary bottle-stopper, larger at the bottom than at the top, shaped to fit in the neck of a bottle, the opening at the bottom of said stopper being located upon one side of the centre, in combination with an obstruction across the neck of the bottle, the same made with an opening upon

one side, thus admitting or emitting the contents of the bottle on a partial rotation of the stopper.

2. In combination with a bottle-stopper, with a through longitudinal perforation, the through-perforated removable neck-piece C, (or lower part of the stopper,) whether the same be thick or thin, and of whatsoever substance it be made, when constructed and used substantially as and for the purpose described.

3. The bottle-neck, herein described, when used in combination with a rotatory stopper, substantially as described.
